UNITED STATES PATENT OFFICE

CLAIR D. LAKE, OF BINGHAMTON, AND FREDERICK A. STOREY, OF ENDICOTT, NEW YORK, ASSIGNEES TO THE TABULATING MACHINE COMPANY, OF ENDICOTT, NEW YORK, A CORPORATION OF NEW JERSEY

TABULATING MACHINE

Application filed September 10, 1925. Serial No. 55,427.

This invention covers improvements in record-controlled tabulating machines, and more particularly improvements in printing tabulators having automatic control devices. 5 Broadly, the invention is directed to the provision of a machine which is much more flexible in the direction of being set up to secure numerous and various results as desired by the operator. Furthermore, the machine is capable of accomplishing novel functions of various sorts not heretofore possible.

A further object of the invention is to provide a tabulating machine which will be capable of automatically accumulating a group 15 of items, taking a total thereof upon a change of control number, then automatically continue tabulating and adding another group of items coordinated to another control number and printing the total of that group when a 20 change of its control number occurs, and finally in automatically printing a grand total of all items previously tabulated, on a change of still another group number. Heretofore such results have required manipulative operations by the operator in addition to automatic operations by the machine. The 25 present machine performs all such operations automatically under control of the record cards.

30 Tabulating machines as at present constructed are arranged to analyze perforated records, add and print items, and to automatically print totals upon a change in the group designating perforations of the record. Heretofore provisions have not been 35 made for taking a total automatically upon a change of one control number and for taking another total automatically upon the change of another control number, particularly in cases where both or a plurality of 40 control numbers change simultaneously.

One of the objects of the present invention is to provide a tabulator of the automatically controlled type in which a succession of different totals may be taken automatically by the machine as the various control numbers change, and also in the further provision of means for permitting the automatic taking of totals in the event that there is a simultaneous change of different control numbers.

Provision is made for taking the proper totals regardless of whether control numbers change sequentially or simultaneously.

Another object is to give such machines a wider range of usefulness by providing 55 mechanism of greater capacity and flexibility, to the end that the machines can analyze records, such as perforated cards, and print data derived therefrom in any predetermined field on the data sheet.

Another object is to provide means whereby totals may be printed wherever desired on the data sheet, irrespective of the location of the counters wherein such totals are accumulated.

Another object is to provide means whereby the group control indications may be in any field or fields on the record cards, from which fields they may be printed in any field on the data sheet.

Another object is to provide means whereby a plurality of counters may add concurrently from the same field on the record card, and print a plurality of classes of totals in a single field or in separate fields on the data 75 sheet.

Another object provides that a plurality of accumulators may add minor and major totals from the same field on the record, and print such totals in the same field or in separate fields on the data sheet, and that said major totals may include said minor totals.

Another object is to provide a plurality of printing and reset cycles occurring sequentially and printing in order the minor, intermediate, and major totals, either in the same or in separate columns.

Another object is to provide means whereby, if a plurality of groups should change simultaneously, their totals will be printed sequentially.

Another object is to provide means whereby on a change of intermediate or major control the machine will stop, take a total, and reset automatically.

Another object is to provide means whereby a plurality of total printing cycles are performed, in which printing either takes place or does not take place, depending on changes of group indicating numbers.

Other objects and advantages will be hereinafter set forth in the accompanying specifications and claims and shown in the drawings, which by way of illustration show what is now considered to be the preferred embodiment of the invention.

In the drawings,

Fig. 9 is an enlarged view, partly in section, of a portion of Fig. 1, showing the zero button control mechanism.

Figs. 10, 10^a, 10^b, taken together, comprise the circuit diagrams of the machine.

Fig. 11 is a diagrammatic representation of the plug board of the machine.

Fig. 12 is a circuit diagram of an alternative zero button controlling circuit.

In its general aspects this machine is similar to previous machines, and its plan of operation can best be learned from the circuit diagram in Figs. 10, 10^a and 10^b. In place of using only five counters as heretofore, we now use ten counters designated 1 to 10 in the diagram, and shown in Fig. 1. The record cards 50 are advanced in the usual way past co-operating upper and lower brushes 51, 52, there being one upper and one lower brush for each column on the record card, or 45 upper and 45 lower brushes.

The lower brushes are connected to the usual multiple plug sockets 53 and the counter magnets of the machine are wired to sockets 54. There are 80 sockets 54 and 45 sockets 53. In place of directly wiring through the total taking contacts in the present machine these total-taking contacts 55 are wired to plug sockets 56. The printer magnets 57 are wired to multiple plug sockets 58. This arrangement is provided in order to permit the cross-plugging from one set of total-taking contacts 55 to printing magnets in any desired section of the printer.

In the present machine one hundred printing magnets 57 are provided, there being

ninety for the ten counters of nine digits each, and ten extra for the printing of asterisks.

The total contacts 55 in place of being wired to a common zero button contact as heretofore are wired to individual contacts 59. The zero button contacts 59 on each counter are arranged to be operated together in unison by a suitable connection 60 which is operated by a controlling magnet 61, in place of being operated manually as heretofore. It will be understood that there is a magnet 61 for each counter, and the energization of this magnet is adapted to close all the zero button contacts 59 pertaining to that particular counter.

The contact blocks of upper brushes 51 are wired to plug sockets 62. These plug sockets 62, by the usual plugs and wires 63 may be connected to sockets 64 of the automatic control unit generally designated as 65. This control unit also has sockets 66 which in the usual way are plugged back to the lower brush plug sockets 53 for controlling purposes.

The control unit is provided with control contacts 67. These contacts 67 are arranged in the customary way so that they are closed upon the energization of the automatic control magnets 68 and remain open when these individual magnets are not energized. There is one pair of contacts 67 for each magnet 68. Suitable means such as manipulative switches 69 are provided for connecting adjacent contacts 67 together in series. The individual contacts 67 are electrically connected to plug sockets 70 as shown in Fig. 10^a. As shown in this figure there are eight pairs of contacts 67, and for convenience of description we have numbered them 1, 2, 3, 4, 5, 6, 7, and 8.

For purposes of further explanation we have, in Fig. 10^a, divided the control unit into three sections. Switches 69 are closed between contacts 1 and 2 and between 2 and 3, so that contacts 1, 2, and 3 are in series. Switches 69 are open between contacts 3 and 4, and between 4 and 5, but closed between 5 and 6. They are open between 6 and 7, and between 7 and 8. Plug connections 71 and 72 are inserted in the outer socket 70 corresponding to contacts 67 in the 1, 2, and 3 positions. Plug connections 73 and 74 are connected to the outer sockets of the 5 and 6 series, and connections 75 and 76 are plugged into sockets 70 of column 8. We thus have contacts 1, 2, and 3 in one group or series, contacts 5 and 6 in another series, and contact 8 in another circuit. In the illustrative wiring herein shown, the 1, 2, and 3 circuit is used for the minor control, the 5—6 circuit is used for the first major (intermediate) control, and the 8 circuit for the major control.

Wire 71 leads through upper card lever 77 to one side of cam contacts C—1. Wire 72 leads to the opposite side of cam contacts C—1. As in previous machines if a change in group number occurs on the 1, 2, 3, posi-

tions one or more of contacts 67 will remain open at the time cam contacts C-1 opens, and the control circuit will be broken between the points X and Y (Fig. 10) so that control 5 relay 78 and motor control relay 79 will be deenergized and the machine will be brought to a stop as in previous designs. Motor control relay coil 79 upon its deenergization opens contacts 80 and allows contacts 81 10 to close. The opening of contacts 80 interrupts the main circuit and the closure of contacts 81 is merely utilized to allow cam contacts L-4 to bring the motor home to the D position.

15 The above has been used in previous machines, but in this present machine provision is also made, by means of the split control device for also automatically stopping the machine on a change in either the intermediate or major controls, represented by columns 5-6, and 8, respectively. After the machine is stopped provision is made for automatically bringing about a total taking 20 operation under the control of the split control device on its major sections, and for thereafter resetting the particular counter or counters to zero. The method by which this 25 is brought about will now be described.

Wires 73 and 74 extend to binder posts 30 82 and 83, while wires 75 and 76 extend to binder posts 84 and 85. Posts 82 and 83 are connected to opposite sides of the relay coil 86, while posts 84 and 85 are connected to opposite sides of relay coil 87. The stopping 35 of the machine on a change of the intermediate, or first major, control in columns 5-6 will first be described.

When contacts 5 or 6 are open current is supplied to relay 86 as follows:—from wire 40 90 through relay 86, cam contacts L-9 now closed, resistance 91, wire 92 and through cam contacts P-7 and lower card lever contacts 45 93 to right side of line. At all times when contacts 5 and 6 are closed, relay 86 is shunted out of the circuit by line 90 through which current passes from line 90 to lines 73 and 74 without passing through 86. When a 50 change in group number occurs in column 5 or 6 one of their corresponding contacts 55 67 will open up and current will flow through relay 86 as above described. The energization of 86 attracts its armature and establishes a circuit through relay coils 94, resistance 95, supplementary stop relay coil 96 and thence through wire 92, cam contacts P-7, and out through right side of line as before.

Cam contacts L-8 and L-9 are timed to 60 close and open synchronously with the opening and closing of contacts C-1.

The energization of coil 96 opens contacts 65 97 and closes contacts 98. Contacts 97 thus open the main motor circuit and contacts 98 provide a secondary path to keep the motor in operation until cam contacts L-4 open at

the D position. If the change in control number occurs in the major control circuit through the 8 column, relay 87 is energized in a similar manner, the circuit being traced as follows:—from left side of line through 70 90, relay 87, cam contacts L-8, resistance 91 and through 92 to right side of line. This sets up a supplementary circuit through the armature of relay 87, relay coil 99, resistance 95, through the supplementary stop relay 75 magnet coil 96 to the right side of line as before.

The foregoing has described how a change in either minor, first major, or second major control has brought the tabulator to a stop. 80 It now remains to describe how totals are automatically printed. These totals may represent the total amounts corresponding to either the minor, intermediate, or major controls, or any or all of them. It will be understood that in certain instances two or more controls may change at the same time. With our present machine it is possible to print the totals corresponding to these controls in the same column on the data sheet, utilizing the 90 same printing bank for printing all totals. It therefore is necessary to provide a sequential operation, otherwise there would be confusion in the printing in one column, since more than one total would tend to be printed 95 at the same time.

In order to have the above sequential printing operations the machine instead of having only one total printing and reset cycle as heretofore, is so arranged mechanically and electrically as to have a plurality of total printing and reset cycles. In the present embodiment three such cycles are provided, but it will be understood that more could be provided if a greater splitting of the control is 100 desired.

If further splitting is desired there will necessarily be the attendant multiplication of controlling relays to stop the operation of the machine and call into action the various 110 printing cycles.

The first of our present cycles is used for total printing the amount or sub-total of the minor control number. The second cycle is utilized for printing a sub-total indicative of the first major (intermediate) control number, and the third cycle is utilized for printing the amount indicative of the grand total or of the second major control number. 115

To secure the above multiple resetting cycle the so-called P cams previously utilized in machines of this type are disposed on a supplementary shaft 100 (Fig. 4) which is geared to the total printing shaft 101 by gearing 102 having a 3 to 1 ratio. The P cams therefore make one revolution for each three revolutions of shaft 101. Inasmuch as certain of the P cams namely, P-1 and P-6, control the reset motor operation these cams will not 120 125

interrupt the reset motor operation or the reset cycle until the end of the third revolution of the total print shaft 101. Another P cam contact, P-4, controls the automatic 5 restarting of the tabulator and this cam contact is so timed that restarting does not take place until after three reset cycles have been completed. The machine therefore contemplates three complete total printing operations. Printing may or may not occur in 10 some of these cycles, depending upon whether various control numbers change or not.

Referring now to Figs. 5 and 9 for an explanation of the zero button mechanism, 110 15 and 111 are the dual resetting shafts of the two banks of the tabulating machine counters. The lower reset shaft 110 is driven in the usual manner, and this shaft through bevel gearing 112, vertical shaft 113, and bevel 20 gearing 114, drives the upper reset shaft 111. Each counter has means for clutching its reset gear 115 with its shaft 110 or 111. The construction is shown in Fig. 9. Gear 115 meshes with a gear 116 having its hub 117 25 shaped in the form of a one-tooth clutch. Adjustably mounted at the proper angular position on shaft 110 or 111 is a collar 118 having a pin 119 freely slidable in a hole in the collar. Pin 119 is fixed in a clutch member 120 which is slidably mounted on one of the resetting shafts and normally held to the left, or out of engagement with 117, by spring 121. Clutches 120 and 117 may be engaged by pushing pin 119 to the right by 30 means of sleeve 122. The shifting of this sleeve may be effected either manually by means of the usual reset button 123, or magnetically by the energization of zero button magnet 61. The armature 61^a of this zero 35 button magnet engages a groove in sleeve 122, substantially as shown. It will be understood that when the reset clutch 120—117 is forced into engagement by the manually manipulated zero button 123 that the parts 40 may be locked in engagement by means of the usual bayonet lock 124. If the parts are 45 shifted magnetically there is no such locking action but the reset clutches engage only while magnet 61 is energized.

50 One way in which the machine can be operated may be set forth as follows:—On a particular counter which accumulates, say, the sub-totals corresponding to minor classifications, the reset devices may be locked by 55 manual adjustment of zero button 123. It may be assumed that it is desired to accumulate amounts of major group classifications in another counter or counters. On that counter or counters the zero buttons are 60 coupled up for electrical manipulation by the operation of certain of the relay circuits previously described. As illustrative of one use of the machine it may be assumed that any three counters are so plugged up to the 65 lower brushes that they all add concurrently

the amounts received from the same field on the card. Then assume it be desired to print in one and the same column three separate classes of totals derived from that field. The first printed total would be that of the minor classifications, the second printed total would be that of the first major (intermediate) classification, and the third printed total would be that of the second major classification, which latter would usually be a grand total 70 of amounts of all the various minor classifications, or a total of all the first major classifications. To secure these results the operator of the machine would cross-plug from the total contact plug sockets 56 of the 75 various counters to the corresponding multiple plug sockets 58 of the printing bank which was selected to print all three classes of totals. It will be seen that the machine herein described provides means for printing 80 totals wherever desired on the sheet irrespective of the locations of the counters on which the totals are accumulated. For instance, the totals may be printed in separate fields 85 on the data sheet, or they may be all on the 90 same field one underneath the other, or they may be partly in one field and partly in another, that is, in the illustration we are considering, two totals may be in a certain field one under the other and the other total may be in any other field desired, provided only that the field is not already being used for another purpose.

95 The method of bringing about the above results will be understood by reference to Fig. 10^a. From circuit 90 two branch circuits are 100 provided including resistances 130 and 131 respectively. Inserted in these circuits are pairs of plug connections 132 and 133, respectively. These pairs of plug connections 105 can be plugged to any pair of sockets 134 which are associated with the various zero button magnets 61. For purposes of explanation it may be assumed that the 132 pair is plugged to the No. 5 counter zero button 110 magnet 61, and the No. 133 pair is plugged to the No. 4 zero button magnet 61. Continuing the tracing of the circuits, from wire 90 a circuit leads from the right side of 115 132 through the armature of relay 99, thence through cam contacts P-8 to wire 92. From the right side of plug connection 133 a similar circuit leads through the armature of relay 94 through cam contacts P-9 and thence to 120 wire 92.

125 Inasmuch as successive printing operations are required cam contacts P-9 and P-8 are so timed as to close at different points in the reset cycle. In the present embodiment these contacts are arranged to close during the second and third resetting cycles, respectively. This is necessary in order to bring about sequential printing operations. It will be understood that during the first resetting cycle previously referred to a total will be printed 130

of the amount standing on No. 3 counter, the zero button of this counter having been manually thrown in and locked. When a change occurs in the first major control number, relay 94 will be energized, thus attracting its armature and closing contacts 174. Whereupon, as cam contacts P-9 are closed at the start of the second total print and reset cycle the zero button magnet 61 controlling the No. 4 counter will be energized, the zero button will be thrown in, contacts 59 will be closed and the total standing on No. 4 counter will be printed. Subsequently this counter will be cleared during the latter part of the same cycle. If at the same time a change has occurred in the second major classification relay 99 would be energized, closing contacts 175 so that upon the closing of contacts P-8 at the time of the total print and reset cycle the zero button 61 corresponding to the No. 5 counter is energized, bringing about the printing of the total standing thereon, followed by the clearing of the counter. The total printing operations may take place from either or both counters whose zero button magnets 61 are plugged to the relay circuits. Any counters may be plugged to these relay circuits by manipulation of plug connections 132 and 133.

After the completion of the one or more total printing operations and upon the completion of the third reset cycle previously referred to, cam contact P-4 (upper contacts) will close and re-initiate the starting up of the tabulator. At the end of the multiple total printing cycle all of the various relays 87, 99, 86, 94 and 96 are deenergized, this being brought about by the opening of cam contacts P-7. P-7 is the only cam contact which can control 86 and 87, they not being subject to control of cam contacts P-8 and P-9.

Fig. 11 shows a diagrammatic view of the plug board of the machine, and from this diagram various operations of the machine can be explained. In the first place, the machine can be used as a simple printing tabulator with or without control unit 65. The present practice with tabulating machines is to provide forty-five effective columns on the card. There are accordingly forty-five sockets 62 connected to the upper brushes. Any selection of these sockets can be plugged to sockets 64 for controlling. The control unit 65, by utilizing sockets 70 and switches 69 may be split at any point, between any columns, as desired.

From sockets 66 connections can be made to any of the forty-five lower brush plug sockets 53. From these forty-five lower brush sockets 53 selective plug connections can be made to any of the eighty sockets 54. If it is desired to accumulate items from the same card field in two or more counters, multiple plug connections can be inserted in sockets 53

and connected to the desired counter sockets 54. Listing of amounts which are secured by plugging to sockets 53 can be effected anywhere as desired on the listing sheet in any of the ten particular fields allocated to the ten counters. It will be understood that although listing can be effected anywhere on the sheet as desired, this listing must always be coordinated to a particular counter because control of the listing circuits is secured through the counter circuits.

Plug sockets 56 and 58 permit the making up of a wide variety of reports. One form has already been described, in which the totals of minor, first major, and second major classifications are all made in the same column. However, it is not necessary that these totals be all printed in the same column, but if desired, they can all be in separate columns. The selection of total printing columns can be made at the will of the operator, and totals accumulated in any counter can be printed anywhere on the record sheet. The multiple sockets 58 provide the means whereby three totals can be printed in any column.

Inasmuch as in our present machine there are more printing columns than there are columns on the record card, it is possible to provide spacing between the printed columns which designate either the control or group indicating numbers. The extra counters herein provided make it possible to split the control numbers and effect printing of them from the circuits associated with counters. This has not heretofore been possible where additional printing sections were not provided.

As it is necessary to keep the reset motor running throughout three revolutions of shaft 101 provision must be made for keeping the reset magnet and reset motor energized for three complete revolutions of the reset shaft. When the reset key 140 is depressed two parallel circuits are established from the left side of line (Fig. 10); one circuit runs through cam contacts P-6 through reset magnet 141, relay coil 142, clutch magnet contacts 143, reset key 140, cam contacts L-2 and out to right side of line through binder post 10; the parallel circuit runs through reset motor 144 and thence through the circuit previously traced to right side of line. The first circuit traced above energizes reset clutch magnet 141 and the second circuit energizes reset motor 144.

Immediately after the reset key is depressed a stick circuit is provided extending through the armature of relay 142 and wire 145 to binder post 6 and thence to right side of line through the circuit previously traced. These circuits are maintained until a period within the third reset cycle. At that time contact P-1 makes, thus maintaining the reset motor in operation. After cam contact

P-1 makes cam contact P-6 breaks, de-energizing the reset clutch magnet 141 and allowing the clutch magnet parts to be shifted to de-clutching position. At the extreme end of this last cycle cam contacts P-1 again open, bringing the reset motor to rest. Just before the machine stops cam contacts P-6 are closed to leave the circuits in condition to be again set up upon the next resetting cycle. The above circuits may also be controlled by the automatic reset cam L-1 in the manner customary in these machines.

A modification of the zero button magnet and controlling relay circuits, which may be used in the present machine, is shown in Fig. 12. This arrangement of circuits is more nearly like previous control systems, and uses series instead of shunt connections. Assuming all plugging of the machine to be the same as already described, and that the same split controlling operations result in the printing of successive minor, first major, and second major totals, our optional control system is as follows:—In Fig. 12 are shown two relays 150 and 151 which directly control the printing of first and second major totals. Contacts 152 of relay 150 become closed, and contacts 153 open upon the energization of magnet coils 154 of relay 150. Upon the de-energization of coil 154 contacts 153 close and 152 open. Likewise upon the energization of coils 155 contacts 156 close and contacts 157 open. Upon the de-energization of 30 contacts 156 open and 157 close.

Connected in series with coil 154 through wires 160 and 161 are the resistance coil 162 and contacts L-9. Upon the energization of coil 154 a circuit is established as follows:—wire 90, wire 163, contacts 152, gooseneck of 35 150, magnet coil 154, wire 160, resistance 162, contacts L-9, wire 92, and through the auxiliary card lever contacts to the right side of line. A similar circuit is established through relay 151 upon the energization of 40 magnet coil 155.

Connected in series with contacts 153 is a magnet coil 170 which is connected through resistance 171 and wire 172 to the magnet coil 96 which controls the opening and closing of 45 contacts 97 and 98 as previously described. Similarly a line extends from contacts 157 through magnet coil 173 and resistance 171 to a joint connection with the circuit through magnet coil 96 to right side of line. It will be understood that magnet coil 170 controls the opening and closing of contacts 174 while coil 173 controls the opening and closing of contacts 175. Cam contacts L-8 and L-9 are timed to open and close synchronously with the opening and closing of contacts C-1. Extending from either side of contacts L-9 and L-8 are pairs of plug wires 50 82, 83 and 84, 85, respectively, which are arranged to be plugged to contacts 67 through

55 sockets 70 in such combinations as may be desired.

The operation is as follows:—If a split occurs in the first major control columns (in this case in columns 5 or 6 of contacts 67) 60 the circuit through plug wires 82 and 83 is open at the time that cam contacts L-9 open and as a result contacts 152 will open and contacts 153 close. The circuit previously described through coil 170, etc. will energize magnet 96, opening contacts 97 and closing contacts 98 to bring the machine to a stop at the D position. Similarly, if a change in group occurs in the second major control (or in the case illustrated, at 8) relay 151 will operate instead of relay 150. When coils 170 and 173 are energized the operation of the circuits through their respective armature contacts 174 and 175 is exactly 65 the same as previously described in connection with the other type of control.

The foregoing has described the plan of operation of our present invention with particular reference to the electric and magnetic features involved therein. Those portions of 70 the circuit diagrams which have not been herein explained in detail are well known in the tabulator art.

The same holds true also as regards the mechanical features of our machine, but in 75 order to help towards a ready understanding of its general features we will give a brief description of its principal parts and their functions.

The record cards 200 (Fig. 1) are fed 80 downwardly one at a time by the picker 201. They pass the upper and lower sets of brushes 51 and 52 contained within section 202 and are restacked at 203.

Power is furnished to drive the tabulator 85 by pulley 204, which in turn receives power from the driving motor through belt 205.

While passing the brushes the cards are analyzed by the brushes and the information derived therefrom is set up in the counters, 90 which are serially numbered 1 to 10. Subsequently the information compiled in the counters is printed, if desired, by the printing mechanism contained in section 206, on data sheet 207 carried by platen 208. The 95 data is printed on the record sheet in any desired arrangement as already explained.

210 is the list-non-list lever, well known in the art, by which many of the listing and printing operations are controlled.

Whenever a printing operation is to take place the type 212 are raised by arms 213, past platen 208. Each bank of type is arrested at the proper time by a catch 214 controlled by a magnet 57 through rod 215, so 100 that when hammers 216 are actuated, the proper type are in position on the printing line. Hammers 216 are actuated by members 217, which are released at the right instant by arm 218.

Arm 213 is fast to shaft 220 and when the machine is set for listing operations the rocking of shaft 220 and raising of the type is brought about by listing cam 221 (Fig. 2) on shaft 222. When totaling operations are to be carried out the type raising is effected by total cam 223 on printing shaft 224. Cams 221 and 223 actuate shaft 220 by means of interconnected arms and levers fully described in the other applications already referred to.

Reset motor 144 drives worm wheel 226 and this in turn drives printing shaft 224 through the instrumentality of printing cam 227 (Fig. 5), controlled by reset clutch magnet 141 through arm 230 and suitable ratchet mechanism designated in general as 231.

The paper feed is effected by the upwardly extending link 235 which cooperates at its upper end with suitable ratchet mechanism on the platen. Link 235 is in turn controlled by the devices designated 236, by means of which the feeding of the paper is controlled in conformance with the work being done, so as to effect single spacing, double spacing, or none at all.

The total taking device will now be described. When printing cam 227 revolves it rocks shaft 240 by means of arm 241 (Figs. 5 and 6). Shaft 240 is connected by interconnecting arms 242 and 243 with shaft 244 to which the total-taking devices 55 of the lower bank of counters is secured. Horizontal arm 245, vertical link 246, horizontal arm 247, and the interconnecting vertical arms 248 and 249 serve to connect shaft 240 to shaft 250, on which the total taking devices 55 of the upper bank of counters is carried. When shaft 240 is rocked by cam 227, shafts 244 and 250 rock in unison and the amounts standing on the counters are derived therefrom by the total taking devices 55 in the well known manner.

Driving motor TM and its wiring are fully described in detail in copending application of Lake and Page, Serial No. 6,981.

The lower card lever contact assembly 260 shown in the conventional diagram at the bottom of Fig. 10 is made up of the 2-point assembly shown in the upper part of Fig. 10 at 265 plus the single point lower card contact 93 in Fig. 10.

We claim—

1. A record controlled accounting machine comprising in combination a plurality of accumulators, total taking mechanism and means for initiating operation of the same to automatically perform a predetermined succession of total taking operations and means for selectively associating the accumulators with the total taking mechanism to permit pre-selection at the will of the operator of the accumulators which shall enter into total taking sequence whereby the number and order of accumulators from which

totals are taken may be varied independently of the predetermined order and number of total taking operations.

2. A record controlled accounting machine comprising in combination a plurality of accumulators, means for automatically taking totals successively from one or more of said accumulators, individual resetting means for individually resetting the accumulator or accumulators from which the total or totals have been taken by the operation of the machine and preselecting means manipulable at the will of the operator for preselecting the accumulators from which the total is to be taken and which are to be reset by the machine operation.

3. A record controlled tabulator including, in combination, a plurality of accumulators, means for automatically initiating a predetermined fixed number of successive total taking operations, and means controlled by the record for predetermined and selecting the accumulators from which totals are to be taken.

4. A record controlled tabulator including in combination a plurality of accumulators, means for automatically taking totals successively from more than one of said accumulators, means individual to each accumulator for resetting the same upon total-taking operations, and record controlled means for predetermined and selecting the accumulators from which the totals are to be taken.

5. A tabulator including a plurality of counters, automatic electrically controlled devices for initiating the taking of totals from several of said counters, and manipulative means for predetermined the counters from which the totals will be taken.

6. A record controlled tabulating machine comprising, in combination, electric means for reading amounts from the records, a plurality of counters for accumulating totals of such amounts, total taking mechanism and means for initiating operation of the same to automatically perform a succession of total taking operations, and means for selectively associating the several counters with the total taking mechanism for pre-selecting at the will of the operator the counters from which the totals are to be taken during the successive operations of the total taking mechanism.

7. An accounting machine including, in combination, electric means for analyzing perforated records, a plurality of counters to set up totals derived from the records, total taking mechanism and means for initiating operation of same to automatically perform a succession of total taking operations predetermined in number, and electric devices controlled by the records for selecting one or more counters from which totals are to be taken during the succession of total taking operations.

8. A record controlled tabulator including,

in combination, a plurality of counters, electric instrumentalities for automatically taking totals successively from several of said counters, electric means controlled by the record for selecting the several counters from which totals are to be taken and means operable conjointly with the aforesaid means and controlled by the record for initiating a fixed number of total-taking operations therefrom.

9. A record controlled accounting machine having a plurality of counters, printing total taking mechanism, means for automatically effecting a predetermined number of repeat operations of said mechanism for taking a succession of printed totals, and means for selectively associating the counters with the total taking mechanism to preselect from which the totals are to be taken.

10. A record controlled accounting machine including in combination with a plurality of accumulators, means for controlling the different accumulators from the records to add items represented thereon as minor, intermediate and major totals respectively, said accumulators for the major totals having means to receive a grand total of the entries constituting the intermediate total, and said intermediate total accumulator having means to receive a total of the minor totals and printing means controlled by the aforesaid accumulators for printing minor, intermediate and major totals and means controlled automatically by the operation of the machine for calling the aforesaid printing device into operation for printing said various totals.

11. The invention set forth in claim 10 in which control means is provided for effecting sequential printing of the minor, intermediate and major totals.

12. A record controlled accounting machine including in combination with a plurality of accumulators, means for controlling different accumulators from the records to add respectively minor, intermediate and major totals, said accumulator for the major totals having means to receive a grand total of the entries constituting the intermediate total, and said intermediate total accumulator having means to receive a total of the minor totals and means including devices controlled in accordance with changes of minor, intermediate or major control numbers of the records for automatically printing minor, intermediate or major totals.

13. A record controlled tabulator with means for adding various classes of totals some of which classes of totals include other classes of totals, and electromagnetic means under control of the records for bringing about the printing of said totals.

14. A record controlled accounting machine including a plurality of counters, a plurality of devices for printing totals from said

counters upon a total sheet, and means intermediate said counters and printing devices for controlling the printing of the totals from any of the said counters by the printing devices on any of various fields of said data sheet.

15. A tabulating machine including a printing mechanism, means for controlling the same to print the total of a group of items, a sub-total of another group of items including said first group and a grand total of all items, and means controlled by the record cards for automatically effecting all said total-taking operations.

16. A record controlled tabulating machine comprising, in combination, electric means for reading amounts from the records; and record controlled means for automatically printing a total of a group of items, a subtotal of another group of items including the first group, and a grand total of all items.

17. A tabulating machine including, in combination, a series of counters, a device for printing totals accumulated by said counters, automatic means for initiating a succession of total-printing operations from said series of counters, and selective means controlling the selection of the counters from which automatic totaling is to take place.

18. A record controlled tabulating machine comprising, in combination, electric means for reading amounts from the records, a plurality of counters for accumulating totals of such amounts, electric means for automatically initiating successive total-printing operations from several of said counters, and manipulative means for selecting the several counters from which the totals are to be taken.

19. A record controlled accounting machine comprising, in combination, a plurality of accumulators, means for accumulating in more than one pre-selected accumulator totals of successive items derived from the records, and means predetermined at the will of the operator for taking the total from one or all of said pre-selected accumulators, said total-taking means including devices brought into operation automatically by the operation of the machine for taking of said totals between entries of successive items from the records into the aforesaid accumulators.

20. The invention set forth in claim 19 in which total-taking devices include sequentially acting devices for successively taking the various totals.

21. A tabulating machine with means for accumulating items from records arranged in groups, some of which groups include other groups or portions thereof, and means controlled by the records whenever the control designation of a group changes, said means being also controlled irrespective of whether or not a plurality of changes of group control designations occur simultaneously, for ini-

tiating totaling operations for all of said accumulating devices and means controlled by the records for determining from which accumulating devices totals shall be actually printed.

5 22. A tabulating machine with means for accumulating items derived from records arranged in groups, some of which groups may include other groups or portions thereof; 10 means for initiating total taking operations suitable for printing totals of any of said groups whenever the control designation of that group changes, and sensing means effective whenever any group designation 15 change occurs, to determine whether or not the totals of other groups are ready to be taken.

23. A tabulating machine with means for accumulating items derived from records arranged in groups, some of which groups may include other groups or portions thereof; 20 means for initiating total taking operations suitable for printing totals of any of said groups whenever the control designation of 25 that group changes, and sensing means effective whenever any group designation change occurs, to determine whether or not the totals of other groups are ready to be taken, and if ready, to cause said other totals to be automatically taken.

24. An accounting machine including a plurality of counters, means controlled thereby for printing totals accumulated in said counters in predetermined fields on a data 35 sheet, and means for selectively coordinating the counters and printing means to print said totals in any desired field on the data sheet regardless of the locations of the respective counters from which the totals are 40 taken.

25. A record controlled tabulator including a plurality of counters, means controlled thereby for printing totals accumulated in said counters in predetermined fields on a data 45 sheet, and means for selectively coordinating the counters and printing means to print said totals in any desired field on the data sheet regardless of the locations of the respective counters from which the totals are 50 taken.

26. A tabulating machine including means for analyzing data on records, means under control of said analyzing means for listing said data on predetermined fields on data 55 sheets, means for accumulating totals of amounts of said data, and means under control of said accumulator means for printing said totals in any predetermined field on the data sheets, regardless of the location of the 60 field on which the data is listed.

27. A record controlled tabulator including, in combination, a plurality of accumulators, means for printing totals from said accumulators on data sheets, and adjustable 65 means to cause totals from a plurality of ac-

cumulators to be printed in the same or in another and different column on the data sheet.

28. A record controlled tabulator including, in combination, a plurality of accumulators, means for printing two or more totals from said accumulators on data sheets, adjustable means permitting two or more of said accumulators to accumulate various classes of totals simultaneously from the same field on the record, and means comprising selectively manipulable electric connections to cause the printing of the various totals on a single field on the data sheet.

29. A record controlled tabulator including, in combination, a plurality of accumulators, means for printing totals from said accumulators on data sheets, adjustable means permitting a plurality of said accumulators to accumulate various classes of totals simultaneously from the same field on the record, and means to cause the printing of the various totals in a single field or in different fields on the data sheet.

30. A record controlled tabulating machine including, in combination, a plurality of accumulators, means for printing totals from said accumulators on data sheets, adjustable means permitting a plurality of said accumulators to accumulate major and minor totals simultaneously from the same field on the record, and means to cause the printing of the major and minor totals in the same field or in different fields on the data sheet.

31. A record controlled accounting machine including in combination with printing mechanism and resetting mechanism, means for effecting a plurality of printing cycles of the printing mechanism and resetting cycles of the resetting mechanism, said means having provisions to effect said cycle sequentially whereby said printing mechanism prints in order minor, intermediate and major totals in the same accumulator on the data sheet in the printing mechanism.

32. A record controlled accounting machine including in combination with printing mechanism and with resetting mechanism, means for effecting a plurality of printing cycles of the printing mechanism and resetting cycles of the resetting mechanism, said means having provisions to effect said cycles sequentially whereby said printing mechanism prints in order minor, intermediate and major totals and means coordinated with said mechanism to cause the printing of the totals in the same field of the record sheet carried thereby or in different fields thereon as desired by the operator.

33. In a record controlled accounting machine, means to sense the records and the control designations thereof, means to accumulate from the records minor, intermediate, and major totals, and means controlled by

the sensing means and having provisions to cause the machine to stop, take a total, and reset automatically whenever an intermediate or major control designation changes.

34. In a record controlled accounting machine, a printing mechanism, means for initiating a plurality of total printing cycles thereof, and record controlled means for causing printing to be effected by said mechanism selectively in all or less than all of said total printing cycles.

35. A tabulating machine having a plurality of accumulators, individual zeroizing control means therefor, an automatic control device controlled by changes in record perforations, and selectively adjustable means for controlling any zeroizing means by said control device.

36. A tabulator having an accumulator, means for resetting the same, a shiftable means for controlling said resetting means to permit or suppress the resetting of said accumulator, and means controlled by changes in record perforations for effecting shifting movements of said shiftable means.

37. An accounting machine having means for accumulating items, means for printing the same and for printing, under control of the accumulating means, the totals which are accumulated, means for controlling the said printing, means to list the items in any selected column of a record sheet, means for suppressing in said column the printing of the total of said items derived from the accumulating means, and means for printing said total derived from the accumulator in any other selected column.

38. An accounting machine having means for accumulating items, means for printing the same and for printing, under the control of the accumulating means, the totals which are accumulated by the accumulating means, means for controlling the printing means to print the items in certain selected columns upon a record sheet, means for suppressing in said columns the printing of the totals of said items derived from the accumulating means, and means for printing said totals thus derived from the accumulating means in different columns anywhere upon the record sheet.

39. A tabulating machine having a plurality of accumulators, each having accumulator elements, a plurality of printing devices, a plurality of perforation sensing means for controlling said accumulator elements, and means for selectively connecting any printing devices for control by any accumulator elements.

40. A tabulating machine having a plurality of accumulators, a plurality of printing devices, a plurality of perforation sensing means, means for selectively connecting any of the perforation sensing means with any accumulator, and means for differently

selectively connecting any printing device for control by any accumulator.

41. An accounting machine having means for accumulating items and means controlled thereby for printing the totals thereof, and selectively manipulative means coordinated with the accumulator and printing means for printing the said totals in any desired column of a data sheet irrespective of any fixed coordination of data columns and the correlated accumulator means.

42. An accounting machine having means for accumulating items and printing the totals thereof, and means for selectively duplicating the printed totals upon any desired columns of a record sheet, at least one of said totals being printed upon the record sheet in a selected location which is unrelated to the position of the accumulating means.

43. A record controlled tabulating machine having a plurality of accumulators, printing devices, and means for controlling the printing devices to print amounts from at least two of said accumulators in the same or in different columns of a record sheet.

44. In a machine for printing totals of various classes of items on a record sheet having a column for each of said classes, the combination of a plurality of devices for accumulating the items in each of the various classes, and means controlled by the accumulating devices for automatically printing any of said totals in any desired column on the record sheet.

45. In a machine for printing totals of various classes of items on a record sheet having a plurality of columns, the combination of a plurality of devices for accumulating the items in each of the various classes, and means controlled by the accumulating devices for automatically printing any of said totals in any desired column on the record sheet.

46. In an accounting machine in combination, a plurality of groups of type carriers, a plurality of totalizers and adjustable connections intermediate the type carriers and the totalizers for setting up upon any desired group of type carriers the amount standing upon any totalizer.

47. In an accounting machine in combination, a plurality of type carriers, a plurality of accumulating elements, and adjustable connections between said carriers and elements for setting up on any one of the type carriers the amount standing on any accumulator element.

48. An accounting machine having a plurality of accumulators and total printing devices therefor, means for pre-selecting among said accumulators certain ones for sub-totalizing operations and others for grand totalizing operations, and means for automatically, by the operation of the machine, bringing about grand or sub-totalizing printing opera-

tions, or both, from the said pre-selected accumulators.

49. The invention set forth in claim 48, in which means is provided for manipulatively selecting the grand and sub-totalizing accumulators from any of a plurality and greater number of accumulators.

50. The invention set forth in claim 48, in which record controlled means is provided for selecting whether a sub- or grand-totalizing printing operation, or both, are to be made, and in which means is provided for bringing about one printing operation or the other, or both, as called for by the record.

51. An accounting machine having accumulator means, printing devices controlled thereby for printing totals upon a record sheet, and means for controlling the printing devices to print the total from said accumulator in any of a plurality of fields on said record sheet.

52. An accounting machine having printing devices arranged to print sets of totals in various fields and zones upon a record sheet, an accumulator device which controls the printing devices in printing totals, and means for connecting any desired set of printing devices with said accumulator to print a total therefrom in any selected field or zone upon the record sheet.

53. The invention set forth in claim 52, in which a plurality of accumulators are provided, with means intermediate the accumulators and printing devices for selectively connecting any accumulator to any printing devices for controlling the same.

54. A record controlled accounting machine having a plurality of accumulators, means for entering items from the controlling records into said accumulators, means for automatically effecting successive operations suitable for taking totals from more than one of said accumulators, means controlled by the record for initiating said total taking operations and means for automatically suppressing the taking of totals from any accumulator or accumulators while totals are being automatically taken from another accumulator or accumulators.

55. A record controlled accounting machine having a plurality of accumulators, means for entering items from the controlling records into said accumulators, means for automatically effecting successive operations suitable for taking totals from more than one of said accumulators, means controlled by the record for initiating said total taking operations, and means for automatically selecting the accumulators from which totals are taken, automatically suppressing the taking of totals from unselected accumulators and automatically permitting the taking of totals from the other.

56. An accounting machine having a plurality of accumulators, means operating auto-

matically during the operation of the machine for instituting a predetermined succession of printed totals, from one or more of said accumulators, and means for pre-selecting at the will of the operator the accumulators from which totals are to be automatically taken.

57. In a tabulating apparatus having a plurality of accumulators and devices for printing totals therefrom, means for automatically initiating a plurality of total printing operations and means for pre-selecting at the will of the operator the accumulators from which totals are taken by the automatic operation of the machine.

58. A tabulator having a plurality of accumulators, individual zeroizing and total taking control means therefor, an automatic control device controlled by changes in record perforations, provisions for splitting said control device to enable independent control to be secured for various single columns or groups of columns upon the record card, and means for selectively coordinating any selection of the split control with any zeroizing and total control means.

59. A tabulator having a plurality of accumulators, individual zeroizing means therefor, an automatic control device controlled by changes in record perforations, provisions for splitting said control device to enable independent control to be secured for various single columns or groups of columns upon the record card, and means for selectively coordinating any selection of the split control with any zeroizing and total control means.

60. In an accounting machine, means to accumulate totals of amounts derived from cards having group control designations and arranged in groups, and means controlled by said accumulating means to print totals of said groups sequentially if a plurality of group control designations should change simultaneously and means providing for the printing of the totals by the printing mechanism in the same column of a data sheet.

61. In an accounting machine, means to accumulate totals of amounts derived from cards having group control designations and arranged in groups, and means controlled by said accumulating means to print totals of said groups sequentially if a plurality of group control designations should change simultaneously, and means for selectively printing the several totals in the same column or in different columns of a data sheet.

62. In an accounting machine, means to accumulate totals of amounts derived from cards having group control designations and arranged in groups, and means controlled by said accumulating means to print totals of said groups sequentially if a plurality of group control designations should change simultaneously, and means providing for

printing totals from said accumulators some in one column and some in another column or columns of a data sheet.

63. A record controlled tabulator having
5 an accumulator, record controlled means for
entering items therein, means for initiating a
total taking operation suitable for taking a
total from said accumulator and means con-
trolled by records for selectively suppressing
10 or permitting the taking of a total from said
accumulator during said total taking opera-
tion.

In testimony whereof we hereto affix our
signatures.
